Inventor:

Frederick B. King
by attorney
Thomas Howard

UNITED STATES PATENT OFFICE.

FREDERICK BUNNELL KING, OF BRIDGEPORT, CONNECTICUT.

SAFETY-RAZOR.

1,287,338.

Specification of Letters Patent. Patented Dec. 10, 1918.

Application filed March 30, 1917. Serial No. 158,572.

To all whom it may concern:

Be it known that I, FREDERICK BUNNELL KING, a citizen of the United States, and resident of Bridgeport, in the county of 5 Fairfield and State of Connecticut, have invented a new and useful Improvement in Safety-Razors, of which the following is a specification.

The object of my invention is to provide 10 certain improvements in the construction, form and arrangement of the several parts of a safety razor whereby the blade is accurately positioned with respect to the guard and the shield and in which the shield 15 is made reversible so that the cutting edge of the blade may be exposed when the shield occupies one position and may be covered and thereby thoroughly protected when the shield occupies another position.

20 A further object is to provide a very simple and inexpensive razor having the advantages above set forth.

A practical embodiment of my invention is represented in the accompanying drawings in which,

Figure 1 represents the razor in side elevation in proper adjustment for use;

Fig. 2 is a front view of the same;

Fig. 3 is a rear view,

30 Fig. 4 is a front view of the razor with the handle removed and the shield in its reversed position for protecting the cutting edge of the blade;

Fig. 5 is a side view of the same;

35 Fig. 6 is a rear view;

Fig. 7 is a side view of the handle detached;

Fig. 8 is a section taken in the plane of the line VIII—VIII of Fig. 4, looking in 40 the direction of the arrows;

Fig. 9 is a section taken in the plane of the line IX—IX of Fig. 2, looking in the direction of the arrows;

Fig. 10 is a section taken in the plane of 45 the line X—X of Fig. 4, looking in the direction of the arrows;

Fig. 11 is a detached front view of the guard;

Fig. 12 is a side view of the same,

50 Fig. 13 is a detached side view of the reversible shield,

Fig. 14 is a rear view of the same, and

Fig. 15 is a detached view of the blade.

The razor blade is denoted by 1 and it is

herein shown as being provided with a cutting edge 2. It is also provided with holes 3 arranged to coact with lugs 4 formed on the face of the guard 5 for removably holding the blade in its proper position on the said guard.

60 The laterally turned lip of the guard is denoted by 6 and a series of transverse slits 7 may be provided along the lip portion of the guard.

The handle of the razor is denoted by 8 65 and it is detachably secured to the back of the guard 5, in the present instance by providing the guard with a flaring recess formed by ears 9 struck from the body of the guard and providing the handle with a 70 wedge 10 arranged to be forced into said flaring recess. To facilitate the manipulation of the razor the handle is preferably arranged at an angle to the guard as shown.

75 The reversible shield for the blade is denoted by 11 and it is arranged to frictionally engage the guard 5. This frictional engagement is provided for by turning the ends of the guard inwardly as shown at 12 and 13 and turning the ends of the shield 11 80 back upon the body portion of the shield as shown at 14 and 15 to provide grooves for the reception of the inwardly turned ends 12, 13, of the guard. These portions 14, 15, of the reversible shield 11 are cut 85 away as shown at 16, 17, and the inwardly turned ends 12, 13, are provided with shoulders 18, 19, so that when the shield is slid onto the guard over the razor blade in one position, it will be stopped with the cutting 90 edge of the razor blade covered and protected, and when slid on to the guard in the reverse position, the cutting edge of the razor blade is exposed a sufficient distance for use in shaving.

95 It will thus be seen that the shield by reason of its reversibility serves not only to hold the blade in position on the guard when ready for use but also serves as a protector for the cutting edge of the blade when the parts are out of their operative position.

It will furthermore, be seen that a very simple interlocking device is provided between the razor blade and the guard for accurately positioning the blade with respect 100 to the guard and the shield.

A razor constructed substantially as herein described comprises a minimum number of

parts and the parts may be readily detached for purposes of cleaning and for the insertion and removal of the blades.

What I claim is:

- 5 1. A safety razor comprising a handle, a guard, a blade, a reversible shield for holding the blade in position on the guard, and coacting means, whereby the shield will expose the cutting edge of the blade when in one position and will cover and protect the cutting edge of the blade when in its other position.
- 10 2. A safety razor comprising a handle, a guard, a blade, a reversible shield frictionally engaged with the guard for holding the blade in position thereon, and coacting means, whereby the shield will expose the cutting edge of the blade when in one position and will cover and protect the cutting edge when in its other position.
- 15 3. A safety razor comprising a handle, a guard, a blade interlocked with the guard, a reversible shield for holding the blade in position on the guard, and coacting means, whereby the shield will expose the cutting edge of the blade when in one position and will cover and protect the cutting edge when in its other position.
- 20 4. A safety razor comprising a handle, a guard, a blade interlocked with the guard, a reversible shield frictionally engaged with the guard for holding the blade in position thereon, and coacting means, whereby the

shield will expose the cutting edge of the blade when in one position and will cover 35 and protect the cutting edge when in its other position.

5. A safety razor comprising a handle, a guard, a blade and a reversible shield for holding the blade in position on the guard, 40 said guard having inwardly turned ends and said shield having turned-back ends forming grooves for the reception of the inwardly turned ends of the guard, the shield being arranged to expose the cutting edge of the 45 blade when in one position and to cover and protect the cutting edge when in its other position.

6. A safety razor comprising a handle, a guard, a blade and a reversible shield for 50 holding the blade in position on the guard, said guard having inwardly turned ends provided with shoulders and said shields having turned back ends forming grooves for the reception of the inwardly turned 55 ends of the guard and having recesses whereby when the shield is slid onto the guard in one position the cutting edge of the blade will be covered and protected and when slid onto the guard in the other position the cutting edge of the blade will be exposed for use.

In testimony, that I claim the foregoing as my invention, I have signed my name this fifth day of December, 1916.

FREDERICK BUNNELL KING.
